SUCTION CLEANER

Harry S. Demaree, Chicago, Ill., assignor to The
Hoover Company, North Canton, Ohio, a cor-
poration of Ohio

Application August 5, 1936, Serial No. 94,360

2 Claims. (Cl. 15—16)

This invention relates to suction cleaners, and particularly to suction cleaners of the type embodying means for reducing the noise of operation caused by air currents. In a general way, 5 the invention comprises the provision of a suction cleaner in which a muffler is attached to the cleaner outlet and constitutes a part of the handle by which the cleaner is directed over the floor covering to be cleaned, a dust bag being provided 10 which has a mouth attached to the upper end of the muffler, so that the exhaust outlet of the cleaner, the rigid muffler, the dust bag and the handle move together as a unit.

One of the objects of the invention is to provide 15 a suction cleaner by which the noise of the air currents will be muffled without undue increase in bulk of the machine as a whole and without making it cumbersome in handling or in appearance. A further object of the invention 20 is to provide a construction of this type in which a dust bag may readily be connected to, or detached from, the outer end of the muffler. A still further object is to provide such a structure in which the muffler portion of the handle is separable 25 from the cleaner outlet and also from the rest of the handle, to facilitate shipment. A still further object of the invention is the provision of a dust filtering bag, and suitable supporting means therefor, such that the dust will collect in 30 the lower end of the bag, away from the main air stream and close to the handle pivot point, so as not to disturb the balance of the machine, and which can be emptied from the upper end. Still further objects of the invention and features 35 of novelty will be apparent upon reading of the accompanying specification when read in connection with the attached drawings to which it relates, and in which:

Fig. 1 is a view in side elevation of a suction 40 cleaner embodying the invention, certain parts being broken away;

Fig. 2 is an enlarged fragmentary view in front 45 elevation of the body of the suction cleaner shown in Fig. 1, certain of the parts being broken away;

Fig. 3 is a still further enlarged fragmentary view, in central longitudinal section, of part of the structure shown in Fig. 1;

Fig. 4 is a reduced fragmentary sectional view 50 taken on the line 4—4 of Fig. 3;

Fig. 5 is a view in side elevation, similar to Fig. 1, but showing the upper portion of the handle permanently connected to the tubular portion of the structure thereof which acts as a muffler;

Fig. 6 is a fragmentary plan view of part of the structure shown in Fig. 5;

Fig. 7 is a view in side elevation, similar to Figs. 1 and 5, but showing a still further modified embodiment of the tubular portion of the handle and the attachment of the upper portion of the handle thereto.

In each of the embodiments shown in the drawings, a portion of the handle is in the form of an enlarged flared tube detachably secured at its end to the outlet of the cleaner body. The invention is shown as embodied in a suction 10 cleaner having a motor arranged with its axis transverse to the direction of movement of the cleaner, but it will be appreciated that the invention can be utilized in suction cleaners of other forms. In the structure disclosed a downwardly 15 facing nozzle 11 is carried by a frame 12 which is supported by spaced pairs of front and rear wheels 13 and 14, respectively, so that the nozzle is held slightly above the carpet or other floor covering to be cleaned. A driving motor 15 is 20 positioned with its axis parallel to the nozzle, and detachably carries at one end a pulley 16, and at its other end a suction-creating fan 17. A power-transmitting belt 18 connects the pulley 16 to an agitator 19, which is mounted for rotation in the 25 nozzle 11, and the fan 17, in the normal operation of the cleaner, serves to draw air into the nozzle 11 and discharge it through a discharge outlet 20, which is an integral extension of a combined outer motor casing and fan chamber 21, within which 30 the motor 15 is fixedly secured. The motor 15 may be inserted into the outer casing 21 through one end thereof and held in place therein by a plate 22, secured by screws 23 to an inwardly extending flange on the casing 21, a similar flange 24 35 being engaged with the motor 15 adjacent the other end thereof. The fan casing portion of the casing 21, between the flange 24 and a flange 25 at the end of the casing is formed to provide a fan chamber volute 26, which extends radially and 40 axially to the center line of the casing as a whole, to merge with the discharge outlet 20, it being understood that the flange 24 extends in a helical direction for part of the circumference. The eye of the fan chamber 26 is formed in a plate 45 27 secured by screws 28, or similar means, to the flange 25. The nozzle 11 has upwardly and rearwardly extending, integral side channels 29 and 30, the former housing the belt 18 and the latter acting as a conduit from the nozzle to the eye of the fan chamber. These side channels are flanged to receive screws 31, or other means, for attaching the nozzle structure as a whole to the frame 12, sealed bearings 32 and 33 being provided 50 whereby the motor 15, including the pulley 55

16 and fan 17, and the outer motor and fan casing 21 are mounted for rotation as a unit relative to the nozzle 11 with its side channels 29 and 30 and the frame 12. The front wheels 13 are mounted on the end of a crank shaft the angular position of which is controlled by a member 34 having an adjusting nut 35 by which the shaft and the wheels may be adjusted to control the height of the nozzle lips above the surface to be cleaned. The combined motor and fan casing 21 is provided with a notched sector 36 which is engaged by a roller 37 on the end of a spring pressed arm 38 pivoted to the frame 12, so that the motor casing and discharge outlet will be releasably held in a vertical or a horizontal position, or may be moved freely within a limited range of intermediate positions. The outer walls of the side channels 29 and 30 are provided with apertures covered by detachable cover plates 39 and 40, the former permitting access to the belt, and the latter providing access to the fan and for attachment of a dusting tool hose connection to the eye of the fan, if desired.

This structure is generally shown in British Patent No. 412,894, accepted July 5, 1934 and sealed September 20, 1934, and the present invention has to do with combining in such a structure, or in any suitable suction cleaner having a pivoted discharge outlet, a muffler construction which constitutes a part of the handle by which the cleaner as a whole may be moved about over the floor covering to be cleaned.

The discharge outlet 20 terminates in a flange 41, to which a tubular muffler 42 is attached by bolts 43, or other suitable means, passing through flange 41 and a flange on a ring 44 at the end of the muffler. The muffler 42 is preferably formed of sheet metal and secured by rivets or other suitable means to the flanged ring 44.

The muffler casing 42 is preferably frustroconical, the surface being preferably inclined at an angle of approximately 7 degrees to the longitudinal axis. At its outer end it carries a reinforcing ring 45, secured thereto by rivets or similar means, and flanged to receive studs 46 to which a bag ring 47 is detachably secured by nuts 48. As shown, a bag 49, of cloth, is provided with a mouth which is secured to the bag ring 47 by a clamping ring 50 which is sewed in the hem of the bag mouth, but it will be understood that a bag of paper, or other suitable dust filtering and dust retaining material may be used and provided with suitable means for attaching it to the ring 45. The bag 49 is formed with a downwardly extending pocket, secured at its lower end by snap fasteners 51, or similar means, to the lower end of the muffler casing, and folded about the bottom portion of the muffler casing 42. The upper end of the bag 49 is provided with a wide mouth through which the bag may be emptied, the material of the bag adjacent the mouth being gathered into folds so that such folded mouth can be slid laterally into a spring-clip 52 which will hold the mouth closed and support the upper end of the bag, such clip being attached by a spring 53, or similar means, to the upper end of a handle portion 54. As shown more clearly in Fig. 3, the handle portion 54 is detachably secured by screws 55 to the upper end of the muffler casing 42 and its reinforcing ring 45. The handle portion 54 is hollow and preferably curved at the top, and carries a switch retaining plate 56 which also acts as an anchor for a power-supplying electric cable 57, the wires 58 extending from the switch down inside of the

handle portion 54 to a plug member 59 in the lower end thereof, for electrical attachment to a plug 60 which is located within the muffler casing 42 and held in place therein by a screw 61. A similar plug is located in the lower end of the muffler casing 42, the wires 63 connecting such plugs 60 and 62 being positioned against the inner surface of the muffler casing and preferably provided with sealing washers 64 of soft rubber, or other suitable material. The plug 60 is held in place by a clamp member 65 of channel shape and engaged by the screw 61. A plug 66 is likewise located in a channel 67 in the outlet extension of the casing 21, which channel communicates with a space in the outer motor casing 21 through which the wires 68 from the plug 66 may be extended to the motor 15, it being understood that the channel 67 does not communicate with the discharge passageway 20 of the fan casing portion of the casing 21. A sealing washer 69 of soft rubber preferably surrounds the plug 66 and the wires 68, and it will be understood that the plug 66 is provided with suitable contacts for establishing connection with the contacts of the plug 62 when the muffler casing 42 is connected to the discharge outlet 20.

A thick lining 70 of sound-deadening material, such as sponge rubber, felt or other suitable material, is positioned within the muffler casing 42, covering substantially the entire inner surface thereof, the rings 44 and 45 being preferably formed with channels into which the ends of the lining 70 may be compressed.

In the embodiment shown in Figs. 5 and 6, the muffler casing 71 is provided with a channeled, flanged ring 72, similar to the ring 44, and secured to the flange 41 of the outlet 20 by bolts 43. The upper end of the muffler casing 71 is provided with a channeled reinforcing ring 73, adapted to receive a spring wire 74 which is adapted to be contracted therein by a lever 75, such wire and lever being carried by a ring 76 which is inserted in the bag mouth and to which the bag mouth is secured by a clamping wire 77. When the wire 74 is expanded it can be engaged over the end of the channeled reinforcing ring 73 and the lever 75 may then be moved to contract such wire 74 into the channel in the ring 73, and thereby secure the mouth of the bag 78 to the muffler casing. The bag 78 is preferably of the same shape and construction in other particulars as the bag 49 shown in Fig. 1, and the casing 71 is lined with sound-deadening material 79, as in the prior modification. The upper handle portion 80 is rigidly and permanently connected to a socket in a yoke 81, the arms of which are engaged against the sides of the casing 71 and secured thereto at 82 by welding, or other suitable means. The handle portion 80 carries a switch plate 83 and the conductor cord extends within the handle portion and is secured against the inner surface of one arm of the yoke 81, entering the upper end of the casing 71 at 84 and extended between the sound-deadening material 79 and the inner surface of the casing 71 to a plug at the lower end of the casing 71, similar to the plug 62 shown in Fig. 3. A cord clip 85 is preferably carried by one arm of the yoke 81, upon which the cable 57 may be stored when the cleaner is not in use.

In the embodiment shown in Fig. 7, a modified form of muffler casing is shown which is curved slightly in a downward direction at its upper end and provided with a flange 87 to receive a bag ring secured thereto by nuts 48, as in

the embodiment shown in Fig. 1. In this embodiment, the upper handle portion 88 is secured in a socket 89 by a rivet 90 or other similar means, the socket 89 being spread laterally to cover a portion of the curved top of the casing 86 and secured thereto by rivets 91, by welding it thereto, or in any other suitable manner. The cable 92 leading from the switch is extended down within the hollow handle portion 88 and enters the muffler casing 86 at the point 93 and from such point between the sound-deadening material 94 and the muffler casing 86 to a plug at the lower end of the muffler casing, as in the embodiment shown in Figs. 1 and 3.

15 It will be apparent that in the embodiment shown in Figs. 1 to 4 the handle is formed in two sections detachable from each other and from the body of the cleaner, which will permit compact packaging of the cleaner, and that in all of the embodiments disclosed the detachable handle is formed in part as a tubular casing for sound-deadening material, to the upper end of which casing the bag is detachably secured. The bag is so formed that the dirt filtered from the air stream will accumulate in the lower pocket, out of the way of the air stream discharged from the fan through the discharge outlet 20, and the bag may be conveniently emptied through

the large opening at the upper end thereof after such end of the bag has been detached from its retaining clip.

What is claimed is:

1. In a suction cleaner, the combination of 5 suction-creating means including a fan chamber rotative about a horizontal axis and having a radially disposed exhaust outlet, a rigid tubular member mounted at said outlet and forming a sound-reducing extension thereof, a short 10 handle fixed to said tubular member, and a filter bag attached at its ends to said tubular extension and handle respectively and having an inlet connection intermediate its ends adapted for attachment to the outer end of said tubular 15 extension.

2. In a suction cleaner, the combination of 20 suction-creating means including a fan chamber rotative about a horizontal transverse axis and having a radially disposed outlet, a tubular 20 muffler forming an extension of said outlet, a handle fixed to the uppermost outer edge portion of said muffler, and a filter bag removably supported beneath said muffler and handle and having an endwise opening inlet intermediate its 25 ends adapted for detachable connection with the outer end of said extension.

HARRY S. DEMAREE.
